Attorney

UNITED STATES PATENT OFFICE.

BENJAMIN BROWNSTEIN, OF ELLWOOD CITY, PENNSYLVANIA.

HAND-PLOW.

1,232,763.

Specification of Letters Patent. Patented July 10, 1917.

Application filed October 16, 1916. Serial No. 125,931.

To all whom it may concern:

Be it known that I, BENJAMIN BROWNSTEIN, a citizen of the United States, residing at Ellwood City, in the county of Lawrence and State of Pennsylvania, have invented 5 certain new and useful Improvements in Hand-Plows, of which the following is a specification, reference being had to the accompanying drawings.

10 This invention relates to certain improvements in hand plows and has relation more particularly to a device of this general character especially designed and adapted for use in connection with snow or other loose 15 material, and is an improvement on the device as embodied in my prior Patent No. 1,202,792, dated October 31, 1916.

It is an object of the invention to provide 20 a novel and improved device of this general character whereby the head or plate is effectively braced in order to compensate for the stress or strain imposed thereupon together with means whereby the forward and rear portions of the plow are formed into 25 scoops to hold the material that is gathered thereby.

The invention consists in the details of 30 construction and in the combination and arrangement of the several parts of my improved hand plow whereby certain important advantages are attained and the device is rendered simpler, less expensive and otherwise more convenient and advantageous for use, all as will be hereinafter more fully 35 set forth.

The novel features of the invention will hereinafter be definitely claimed.

In order that my invention may be the better understood, I will now proceed to describe 40 the same with reference to the accompanying drawings, wherein

Figure 1 is a view in side elevation of a hand plow constructed in accordance with an embodiment of my invention, the handle 45 being shown in fragment;

Fig. 2 is a rear elevational view of the device as disclosed in Fig. 1;

Fig. 3 is a top plan view of the device as herein embodied; and

50 Fig. 4 is a front elevational view of my improved plow as herein disclosed.

As disclosed in the accompanying drawings, H denotes the head of my improved plow which is preferably formed of sheet metal and is bent longitudinally at one end portion to afford a short arc 1 extending

rearwardly and its opposite end portion is bent longitudinally to afford a long arc 2 disposed forwardly. The intermediate portion 3 of the head H is substantially straight. 60

4 denotes an operating handle of predetermined dimensions and having one end bearing against the rear face of the head H at substantially the transverse center thereof and at a point adjacent the junction of the 65 intermediate portion 3 and the arc 2.

The end portion of the handle 4 adjacent the head H is angular in cross section, as indicated at 5, and coacting with opposed faces of said angular portion 5 are the 70 brackets or clips 6 preferably L-shaped in form and which are suitably secured to the head, whereby the handle 4 is effectively attached thereto.

7 and 8 denote braces interposed between 75 the outer extremity of the angular portion 5 and the corner portions of the head H, said braces 7 being of a length less than the length of the braces 8 and each pair of braces 7 and 8 are diametrically opposed, as 80 is believed to be clearly shown in the accompanying drawings. The braces 7 and 8 coacting with the curved portion 2 of the head are secured to said curved or arc portion at the central portion thereof, while the 85 remaining two braces 7 and 8 are secured to the curved or arc portion 1 at substantially the center thereof. The braces 7 and 8 preferably comprise flat strips of metal.

The side margins or edges of the head H 90 are provided with the oppositely directed flanges preferably afforded through the medium of the plates 9 and which plates serve as an effective reinforce for the head and especially as relates to torsional strain. The 95 flanges as afforded by the plates also materially facilitate the practical use of the plow. It is also preferred that the forwardly directed flanges afforded by the plates 9 terminate in the connecting plane 100 between the outer free edge of the arc or curved portion 2 and the outer bow portion of the arc or short curved portion 1, while the opposite or rearwardly directed flanges afforded by said plate occupy the plane extending from the free or outer end of the short arc or curved portion 1 and the inner portion of the long arc or curved portion 2. 105

From the foregoing description, it is thought to be obvious that a hand plow constructed in accordance with my invention is 110 of an extremely simple and comparatively

inexpensive nature and is particularly well adapted for use by reason of the convenience and facility with which it may be assembled.

5 It is to be understood that the present invention is not limited to the details of its illustrated embodiment, but may be embodied in other constructions of hand plows within the scope of the following claims.

10 I claim:

1. A device of the character described comprising a head having its opposite end portions disposed longitudinally on reversely directed curves, a handle secured to the head intermediate the curved ends thereof, a longitudinal margin of the head being provided with forwardly and rearwardly directed flanges.

2. A device of the character described comprising a head having its opposite end portions disposed longitudinally on reversely directed curves, a handle secured to the head intermediate the curved ends thereof, each longitudinal margin of the head being provided with forwardly and rearwardly directed flanges.

3. A device of the character described comprising a head having its opposite end portions disposed longitudinally on reversely directed curves, a handle secured to the head intermediate the curved ends thereof, and plates secured to the longitudinal margins of the head and extending beyond opposite faces of the head to afford flanges.

35 4. A device of the character described comprising a head having its opposite end portions disposed longitudinally on reversely directed curves, a handle secured to the head intermediate the curved ends thereof, the longitudinal margins of the head being pro-

vided with forwardly and rearwardly directed flanges, the forwardly directed flanges bridging the space between the intermediate portion of the head and the forwardly directed end portion thereof.

5. A device of the character described comprising a head having its opposite end portions disposed longitudinally on reversely directed curves, a handle secured to the head intermediate the curved ends thereof, the longitudinal margins of the head being provided with forwardly and rearwardly directed flanges, the rearwardly disposed flanges bridging the space between the intermediate portion of the head and the rearwardly curved end portion of the head.

6. A device of the character described comprising a head having its opposite end portions disposed longitudinally on reversely directed curves, a handle secured to the head intermediate the curved ends thereof, and forwardly and rearwardly directed flanges disposed longitudinally of the head.

7. A device of the character described comprising a rectangular head having its opposite end portions disposed longitudinally on reversely directed curves, a handle secured to the head at substantially the transverse center of the head and adjacent the junction between the intermediate portion of said head and one of the curved end portions, and braces interposed between the corners of the head and the handle at a point inwardly of the head.

In testimony whereof I hereunto affix my signature in the presence of two witnesses.

BENJAMIN BROWNSTEIN.
